UNITED STATES PATENT OFFICE

105,450

DESIGN FOR A PET FEEDER STAND

Ira R. Clifton, Cincinnati, Ohio

Application May 10, 1937, Serial No. 69,282

Term of patent 7 years

To all whom it may concern:

Be it known that I, Ira R. Clifton, a citizen of the United States of America and a resident of Cincinnati, in the county of Hamilton and State of Ohio, have invented a new, original, and ornamental Design for a Pet Feeder Stand, of which the following is a specification, reference being made to the accompanying drawing, forming a part thereof.

The figure is a perspective view of a pet feeder stand showing my new design.

I claim:

The ornamental design for a pet feeder stand as shown.

IR A R. CLIFTON.
